5 Claims. (Cl. 74—818)

This invention is for an indexing apparatus for selectively adjusting a movable element to a predetermined setting from a remote location. The invention, while being applicable to various operations, is particularly useful for operating relatively heavy movable parts whose position must be accurately adjusted. The invention is especially useful for rotating marking dies for marking steel billets and slabs with data that is usually marked on such products to identify the billet or slab as to the heat number, date and perhaps coded information as to its composition, or like markings.

In billet marking machines disclosed in certain prior applications in which we are co-inventors; namely, Serial No. 737,041 filed May 22, 1958, now Patent No. 3,020,834, granted February 13, 1962, Serial No. 765,513, filed October 6, 1958, now Patent No. 3,002,918, there is disclosed a marking device having a marking head comprised of a plurality of gear wheels in side-by-side relation, each being independently rotatable and each having an impression forming marking character on the outer ends of the gear teeth thereof. Mechanism is provided for advancing the marking head into contact with the edge of the slab or billet and when contact has been made, the marking head is struck a heavy blow, whereupon the characters on those gear teeth of the marking head which contact the billet make an impression in the billet. The marking head is then retracted and in the retracted position each gear die is engaged by a separate indexing gear. The selective rotation of the indexing gears may then be effected to rotate the gear dies to bring different characters into marking position. The indexing gears are rotated in step-by-step increments through pawls which are reciprocated by pneumatic cylinders, each reciprocation of a pawl rotating the indexing gear one tooth, and such rotation is in turn transmitted to the gear die.

It is necessary that the indexing be effected from a consol or panel remote from the marking head and that it be rapidly but accurately effected. The gear dies must be heavy to withstand the impact, and the entire system must be fool-proof and secure against error due to jarring, failure of a pawl to effectively ratchet, or error due to some bounce or inertia effect that occurs when heavy parts such as are here involved are moved rapidly or stopped or their direction of movement suddenly reversed.

In a copending application Serial No. 765,513 filed October 6, 1958 in which we are co-applicants, the indexing is effected through electric circuits responsive to the reciprocation of the pawl that rotates the indexing gears and which include stepping relays that are energized through such limit switches. While this system is normally satisfactory, it is subject to possible error since it really counts the reciprocations of an operating pawl and not the actual rotation of the indexing gear. Bouncing or jarring or inertia may result in a movement of a pawl with no corresponding movement or improper movement of an indexing wheel. Should this happen, the stepping relay would reach the intended setting ahead of or out of phase with the actual turning of the gear die to the selected character, so that an erroneous marking might be made, and the operator at the consol would be unaware of it because he must assume that the indexing mech-

2

anism has functioned properly. If there were but one marking gear and one indexing gear and one pawl involved the chance of error from the cause would be relatively slight, but since there are usually several marking dies, perhaps nine or more, the chance of error is multiplied and this is especially so since the mechanisms for indexing the several dies must be confined in a relatively small space.

An object of the present invention is to provide an indexing system which is responsive to the movement of the indexing gears directly as distinguished from movement of the pawls, whereby any error due to failure of an indexing gear to properly rotate cannot occur. Since the indexing gears are meshed with the marking gears, the marking gears must correspondingly move with each increment of movement of the indexing gears, and error cannot occur.

A further object of our invention is to provide an indexing mechanism that will not be disturbed by the jarring of the machine or possible bounce of any of the parts.

A further object of our invention is to provide an indexing system which will continue to operate until the gear die has moved to its selected position and provide an indication at the control panel or consol only when the selected character is in marking position.

A further important object of our invention is to eliminate stepping relays from the selector circuit and provide switch means operated by the movement of the indexing gears to operate the pawls until the selected character is in marking position, simplification of the circuits being also accomplished by elimination of stepping relays.

These and other objects and advantages are secured by our invention as will more fully appear from the detailed description thereof in conjunction with the accompanying drawings, in which:

FIG. 1 is a more or less schematic view of the indexing gears and operating mechanism therefor with a portion of the circuits for controlling the same;

FIG. 2 is an elevation on a larger scale showing the indexing gear and the contact wheel operated thereby;

FIG. 3 is a transverse section through one of the contact wheels in the plane of line III—III of FIG. 2; and

FIG. 4 is a schematic simplified circuit diagram for the system; and

FIG. 5 is a fragmentary view showing an alternate form of contactor for use in the indexing head, the view being partly in vertical transverse section and partly in elevation.

In the drawings we have shown a single indexing gear and associated parts and control circuit therefor, and it is to be understood that this is substantially duplicated (except for the rectifier and transformer) for each marking die or other member to be indexed.

Referring first to FIG. 1 of the drawings, we have shown the marking head in dotted lines, and it is designated generally as 2. It is shown in the retracted position and it moves toward the right as viewed in FIG. 1 to engage a face of the billet or slab to be marked. A single gear die is indicated at 3 and the end faces of the teeth have character imprinting dies thereon, one character on each tooth. Typically these characters may comprise the numerals 0 to 9, or a succession of letters of the alphabet. The tooth in position 3a of the gear die 3 is the one which is selected to mark. The construction and operation of the marking head and the correlated movement of the indexing head is more fully described in application Serial No. 737,041 and brief reference is made thereto only to enable the objects and purposes of the present invention to be more fully understood.

The indexing head 4 in the billet marker above re-

ferred to is mounted on a vertically movable support 4a by which the indexing head is moved into and out of engagement with the gear dies of the marking head. The indexing head comprises a supporting frame 5 in which is slidably mounted an axially reciprocable rod 6 which carries a pawl 7. The indexing head has side plates 8 which support a shaft 9 on which the indexing gear wheel 10 is rotatably mounted. The pawl 7 rides or ratchets over the teeth of the indexing gear as it moves to the right as shown in FIG. 2, and it engages a tooth on the gear when it moves to the left to rotate the indexing gear in a counter-clockwise direction as viewed in this figure. This movement of the indexing gear is transmitted to the gear die 3 to rotate it one increment. Fixed in the indexing head is a pivoted holding pawl 11 that holds the indexing gear against free rotation and prevents any over-travel. It is normally held in gear locking position by a leaf spring 12 and is tripped by an abutment 13 on the slide rod 6.

As explained above, and as more fully described in the copending applications above last referred to, we have here shown but one indexing gear and operating rod 6, but the complete machine embodies a head in which there would be several of these gears and operating bars in side-by-side relation and the single shaft 9 would carry all of the indexing gears.

The rod 6 has an operating extension 14 that passes through a cylinder 15, the rod having a piston 16 affixed thereto inside the cylinder. The cylinder has a port at each end in which is entered a pipe, the pipe at one end being designated 16a and at the other end 16b. These pipes lead to a slide valve 17 of a well known type in which there is a reciprocating valve element 18. The valve body has exhaust ports 19 and two spaced air inlet ports leading from an air supply pipe 20. The arrangement is such that when the valve 17 admits air from pipe 20 to one end of the cylinder 15 the other end of the cylinder is vented to atmosphere. The valve is shown in the drawings in a position where piston 16 has completed its stroke to the left and the operation is about to reverse. This is the normal or "rest" position of the parts. The valve is magnetically operated in one direction and then the other, and this is indicated in the drawings where the ends of the slide valve project beyond the valve housing and constitute armatures 17a and 17b for solenoids 17c and 17d respectively. These solenoids are energized through micro-switches 21 and 22 that are arranged to be engaged by abutments 21a and 21b respectively on the piston rod 14 so positioned that the micro-switches will be tripped at the opposite limits of travel of the piston 16.

The switches 21 and 22 each have one pole connected to a current supply line 23. The other pole of switch 21 is connected through wire 24 with solenoid 17c and the other pole of switch 22 is connected through wire 25 with solenoid 17d. The other terminals of the solenoids are connected to a return conductor indicated by the ground connections G in FIG. 1.

In the operation of this part of the apparatus, assume that abutment 21a on the piston rod is closing the switch 21. Current flows from line 23, through the switch 21 and wire 24 to the solenoid 17c, causing the element 18 of the valve 17 to be shifted to the right as viewed in this diagram. When this shift is made, the left-hand port 19 will be closed and air can enter from pipe 20 and flow through pipe 16b to the left end of cylinder 15. This will drive piston 16 to the right, moving the pawl 7 on rod 6 to the right of gear 10. As piston 16 reaches the right-hand limit of travel, abutment 21b engages switch 22 to close it, energizing solenoid 17d to shift the slide valve to the opposite limit of its travel, so that the left port 19 is vented to atmosphere and air flows from pipe 20 into pipe 16a and the opposite end of the cylinder 15 to drive piston 16 to the left. As the rod 6 moves to the left, pawl 7 rotates the index gear wheel 10 through one increment. As the piston returns again to the left-hand

limit of travel, switch 21 is tripped and the cycle is repeated, and this operation will continue as long as wire 23 remains energized. The present invention is primarily concerned with the opening and closing of the circuit to the wire 23 and associated circuits. A magnetic single pole double throw switch or relay is shown at 26 in FIG. 1, and when this switch is in the position in which the switch is there shown, the wire 23 is connected with a source of energizing current. The relay has a coil 26a and an armature 26b and is biased to normally assume the position shown in FIG. 1 when the coil 26a is not energized.

According to the present invention, the rotation of the indexing gear wheel 10 in combination with a selector switch at the operator's consol controls the operation of the switch 26. As here shown, there is a multiple contact switch 27 in the form of a second gear wheel supported on a shaft 28 on the indexing head with the teeth of this gear wheel meshing with the teeth of the gear wheel 10. It might have wide pitched teeth, like the gear die 3, but is here shown as having two teeth operating as a single tooth between two teeth of the indexing gear wheel 10. Gear wheel 27, as best shown in FIGS. 2 and 3, is a fiber gear or wheel made of insulating material. On one face is a conducting disk or plate 29 of metal. There is a spiral series of contact posts on this plate which pass through the face of the switch, the ends of which are exposed on the opposite surface of the switch 27. Each pin is arcuately and radially separated from the others and they are all designated with the letter P in FIG. 2.

There is a contact brush 30 that bears against the metal disk 29. There is a support 31 at the face of the gear opposite disk 29 having a series of wipers or brushes 32 thereon, there being an electrically separate brush or wiper 32 for each pin P. They are so positioned that they bear against the surface of the gear wheel 27 on a line corresponding to radius R in FIG. 2, and each wiper is wide enough to contact only one of the pins P. Thus, as the gear wheel 27 is rotated, first one pin P and then the next will in turn be carried into contact with one of the wipers 32. There is a separate wire 33 leading from each of these wipers 32 through a multiple conductor cable, designated as 34, to a selector switch 35 that may be located in a consol or control panel remote from the marker. This is usually nearby, but comfortably removed from the machine.

At the selector switch the cable branches out into a number of wires 36 corresponding to the number of wires 33 and wipers 32, and each of these wires terminates at a switch contact 37. There is an adjustable switch arm 38 manually adjustable to selectively engage any one contact 37, so that when the switch arm 38 is on a selected contact, a circuit may be completed from the selected contact to a corresponding wiper 32, and when the gear 10 moves to the right position, the circuit will be closed through the pin P for that wiper to the disk 29 and brush 30.

Referring now to FIG. 4, the manual selector switch 35 is indicated in the upper left corner of the figure, and the multiple contact switch on the gear 27 is indicated below it. It is here diagrammatically indicated for clarity of illustration as a switch having a number of contacts arranged in an arc rather than being shown according to its actual construction, but each contact 32 corresponds to a contact 32 of FIG. 2.

The selector system with the multiple contact switches 65 is preferably operated at low voltage, wherefore current from supply lines 40 and 41 is passed through the primary of a step-down transformer 43. The secondary of this transformer is designated 44, and one side of the secondary is connected to a wire 45 leading to one side of a relay coil 26a of switch or relay 26. The other side of the relay coil is connected through wire 46 with manual selector switch arm 38. The contacts 37 of this selector switch lead through wires 36 and cable 34 to wires 33 leading to the several brushes 32. The circuit from wipers 32 is through one of the pins P and disk 29 (indi-

cated as a swinging switch arm 29' in FIG. 4), brush 30 through wire 46 to the other side of the secondary 44 of the transformer 43. Thus it may be seen that only when the circuit may be completed through the selected contact on the selector switch 35 and the corresponding pin P on the gear-actuated multiple contact switch 27 will the electromagnet 26a of the control switch or relay 26 be operated.

Wire 40 connects to both contacts 26c and 26d of the relay switch 26. Contact 26e of the relay switch connects to wire 23 leading to the two micro-switches 21 and 22 as above described, and through one or the other valve-operating solenoids 17d-17c to ground or return current supply line 41. There is a switch 47 in line 40, diagrammatically indicated in FIGS. 1 and 4 that is closed when the indexing head 4 moves down into the operating position to closed position, and which is biased to open when the indexing head is raised.

When the condition arises that the circuit is closed through the manual selector switch 35 and the gear-operated switch, relay magnet 26a is energized, lifting the armature of the relay to open the circuit from contacts 26c and 26e of switch 26 and close a circuit across contacts 26d and 26f. Current then flows from line 40 through contacts 26d and a signal lamp 49 to ground. A branch circuit 50 leads through relay winding 51 to ground. The energizing of relay 51 closes switch 51a. This switch is in series with like switches for each of the other indexing wheels of the indexing head, for which reason the balance of the circuit is indicated in dotted lines. If there are, for example, nine indexing wheels, a switch corresponding to 50-51a for each wheel would have to close, whereupon a circuit would then be complete through a main indicator lamp 52. Also the circuit would then be established through this series of switches and line 53 to the stamp-operating switch 54, so that when the operator pushed the switch 54 down, current would flow through this switch to those electro-pneumatic devices that move the marking head 2 toward the object to be marked and effect the marking operation as more fully described in the last two applications above mentioned.

The operation may now be completely followed. The operator sets selector switch arm 38 to the character which he wants next to be brought into marking position. When the indexing head 4 moves down to operating engagement with the marking head 2, switch 47 is closed, so that current flows through line 40, contacts 26c-26e of switch 26 to micro-switch 21, which at that time is closed. This initiates the reciprocation of piston 16 to move the rod 6 and turn the indexing gear 10, and thereby turn marking die 3. Rotation of the indexing wheel 10 also rotates contact gear wheel 27. The reciprocation of the piston 16 continues automatically upon the closing of switch 47 until a circuit is completed through the selected contact of switch 35 and the corresponding contact of switch 27 to energize relay winding 26a to open the circuit between contacts 26c and 26e to stop further reciprocation of the pawl 7. It will be seen that until switch 47 is closed by the support 4a lowering to a position where indexing gear 10 meshes with gear die 3, no operation of the indexing gear can be effected. It is therefore possible for the operator to pre-select the position of the switch arm 38 when the support 4a is raised, with no operation of the indexing gear taking place. Since the complete machine embodies several marking dies and, therefore, several selector switches 35, it is an advantage that the manual selector switches can be adjusted at the operator's console while the marking cycle is being carried out, and thus be set in advance of the return of the marking head to its retracted position when the support 4a is next lowered.

For the further utility of the device, and to reassure the operator that the proper number has been set and enable the operator to make correction if he has set his selector dial at the wrong setting, the system may include a second switch 60 operating with a gear wheel 27, as

indicated by the diagram in FIG. 4. This switch has contacts 61 corresponding in character sequence to the ones above it in the diagram. Each contact 61 has a wire 62 leading therefrom to a cable 63, the wires of which lead to the several contacts of a so-called "nixie" lamp 64, which is a glow tube having a number of characters therein, a selected one of which will glow when its circuit is energized, such lamps being well known in the art. The common terminal of the nixie lamp is connected to one output 65 of rectifier 66. The other output terminal of the rectifier is connected through line 67 with the moving contact 69' of the switch 60. The lamp operates on 200 volts, direct current. The input terminals of the rectifier are connected across lines 68 leading to the output terminals of the voltage step-up transformer 69. The primary of this transformer is connected through wire 70 across the current supply lines 40 and 41.

The circuit described causes the selected character on the nixie light to glow when the indexing wheel 10 has moved to the chosen position, which will be at the same time lamp 49 is lighted, giving the operator two signals that the particular wheel is at the pre-selected position. It will be apparent to those skilled in the art that while two switches operating in unison are shown in the diagram, the effect of two switches may be secured electrically through the use of blocking circuits or relays separating the alternating and direct current circuits, and that the simplified wiring diagram of FIG. 4 is more or less symbolic or schematic.

In the particular system shown, the marking wheel or gear dies is separate from the indexing gear wheel, but in some instances, as for example with rubber stamps used for making boxes, the indexing wheel might itself be a type of marking wheel, or the wheel switch 27 might be a marking wheel, or one wheel could combine all of the functions of the three wheels here shown.

However, the system here shown is especially adapted for a billet or slab marker where the gear dies are heavy, the setting of the dies fast, and bouncing or jarring is likely to occur. If the pawl 7 fails to catch on the indexing gear, the mechanism must continue to operate until it does, or for such length of time that the operator knows that there is a failure of the indexing wheel to turn, and shut the machine down for repair or adjustment. Since all operations of the contact gear 27, the marking wheel 2 and the indexing wheel 10 occur when the gears are in mesh, movement of any gear will reflect correspondingly on the others.

In FIG. 5 we have shown an alternative form of contactor on the indexing head. In this view, the gear 27' corresponding to gear 27 in FIG. 2 is made of conducting material, and instead of having a succession of contact pins P as in FIG. 2, it carries a single brush, 27a. Alongside the gear 27' there is a fixed arm or plate 31' in the location of part 31 of FIG. 2, but in this case it has a circular series of equally spaced contacts 32' thereon arranged to be engaged in succession by the brush 27a as the gear 27' rotates. A wire 33' corresponding to wires 33 of FIG. 2 leads from each contact 32' while a brush 30' connected to wire 46 is the counterpart of brush 30 in FIG. 2, in that a circuit may be completed through brush 30' to gear 27' to brush 27a and from this brush through a contact 32' on fixed support 31 to wire 33'. Except for the rotating multiple contact switch construction, the circuits for FIG. 5 would be the same as above described.

It will be understood that while we have shown one embodiment of our invention, various changes and modifications may be made in the construction and arrangement of parts within the contemplation of our invention.

We claim:

1. An indexing apparatus comprising an indexing gear, a pawl mechanism movable between two positions engaging the indexing gear in one direction of movement only to rotate the gear incrementally, a fluid motor includ-

ing a reciprocating piston and a rod, the rod extending beyond the motor and connected to the pawl mechanism for imparting rectilinear motion thereto, a fluid slide valve having a reciprocating slide element therein, armatures connected to the slide element for movement therewith and extending beyond the valve at opposite ends of the slide element, conduits flow-connecting the fluid slide valve with the motor for introducing fluid from the valve to operate the motor piston selectively from one position to another whereby the motor piston rod is reciprocated, solenoid coils connected in parallel and coupled magnetically to each of the armatures, a source of current connected to each of the solenoid coils, a switch connected in series with each of the solenoid coils and the source of current, both switches being normally open and positioned for tripping alternately by travel of the pawl mechanism such that the coils are energized alternately to move the slide element of the valve for controlled movement of the motor piston by fluid ported from the valve selectively on both sides of the piston, a relay with a contactor connected in series between the current source and the switches and with a coil for operating the contactor to close the circuit from the source to the switches in one position and to open the circuit in another position, a manually adjustable switch with a plurality of contacts and a contactor selectively movable to any one of the contacts, a rotary switch with a contactor operatively connected to the indexing gear for rotation and including a plurality of contacts corresponding to the contacts of the selector switch, the corresponding contacts of the rotary switch and the selector switch being electrically connected, the electrical source being connected serially to both the contactor of the selector switch and the contactor of the rotary switch whereby a closed circuit is formed joining the source to the selector switch contactor and one of its contacts to a corresponding contact of the rotary switch and its contactor back to the source, and the relay coil being in series connection with the source and the selector switch contactor whereby the coil is energized when corresponding contacts of the selector switch and the rotary switch are contacted by the contactors of such switches to move the relay contactor to the other position to open the circuit from the source to the switches connected to the solenoid coils for stopping the action of the valve and motor and the rotation of the indexing gear.

2. An indexing apparatus as defined in claim 1 including a support movable from a first position to a second position; the indexing gear being mounted for rotation on the support; a gear die with marking indicia on the faces of its teeth and positioned to mesh with the indexing gear when the support is in the second position only; and a switch closed by the position of the movable support in the second position to connect the electrical source with each of the switches of the solenoid coils, and the contactors of the rotary and manual selector switches; the

switch being open when the support is moved to the first position whereat the indexing gear and the gear die are disengaged.

3. An indexing apparatus as in claim 1 wherein the rotary switch contacts are pins in radially spaced arrangement on a wheel and a series of brushes are fixed in the path of travel of the pins with one brush positioned for wiping contact with each pin, each of the brushes being electrically connected to a contact of the selector switch, 10 and the source of current being connected to each of the pins whereby a circuit from the current source is established through a pin, a brush, a contact of the selector switch, the selector switch contactor and back to the source when a contact brush and pin of the rotary switch is closed in corresponding relation to a particular contact closed on the contactor of the selector switch.

4. An indexing apparatus as in claim 1 wherein an indicating circuit including an indicating device is connected to the relay contactor when it is moved to the 20 other position, the contactor electrically connecting the indicating circuit with the source of current when the relay is in such other position which is effected when the relay coil is energized by completion of a circuit from the source through a selector contact and corresponding contact of the rotary switch.

5. An indexing apparatus as in claim 1 wherein a further rotary switch is provided with a contactor mechanically connected to the rotary switch for movement in unison therewith and having a series of contacts corresponding in number to those of the rotary switch and similarly contacted by its contactor, the source of current being connected to the further switch contactor, and indicating means serially connected between the contacts of the further rotary switch and source of current for visual display of the particular one of the further rotary switch contacts made by its contactor which is indicative of the particular one of the contacts of the rotary switch made by its contactor.
